LOOM REWARPING ATTACHMENT, AUTOMATIC WARP TENSION PLATE AND SECTIONAL GUIDE

Filed June 30, 1931

UNITED STATES PATENT OFFICE

JOHN DENT, OF NATIONAL MILITARY HOME, LOS ANGELES COUNTY, CALIFORNIA
 LOOM REWARPING ATTACHMENT, AUTOMATIC WARP TENSION PLATE AND SECTIONAL GUIDE

Application filed June 30, 1931. Serial No. 547,838.

This invention relates to an improved loom rewarping attachment, automatic warp tension plate and sectional guide. The principal object is to provide means for taking warp from the spool rack, taking up all warp slack and arranging the warp upon the warp drum in sections as desired.

More specifically the invention comprises an adjustable tension plate and slack eliminator adapted to be supported by the heddle bar and loom support between the spool rack and warp drum to guide the warp and eliminate the slack therein previous to its being wound upon the drum, said eliminator including means for insuring an even distribution of the warp upon the warp drum sections, means being also provided for guiding the warp to the proper drum section and preventing "jumping" of the warp during this operation.

With the foregoing and other objects in view, the invention consists in the combination and arrangement of parts to be herein-after fully described, pointed out in the claims and illustrated in the accompanying drawing which forms a part of this application for patent and in which—

Fig. 1 is a top plan view of the invention illustrating its application.

Fig. 2 is a view of the invention in side elevation.

Fig. 3 is a cross sectional view, enlarged, on the line 3—3 of Fig. 2.

Fig. 4 is an end view of Fig. 2 taken on the line 4—4 thereof.

Fig. 5 is a fragmentary plan view, inverted, of Fig. 2, taken on the line 5—5, one connecting bolt being shown in section.

Fig. 6 is an enlarged fragmentary sectional view of Fig. 1 showing the nipper attachments for the drum guides.

Fig. 7 is a sectional view through the drum illustrating the application of the warp cutter employed.

Fig. 8 is a side view of the warp cutter.

Like reference characters denote corresponding parts throughout the several views.

The invention proper comprises a sectional guide and tension plate comprising the sliding sections 1, 2, one end 3 of the section 1 be-

ing curved for resilient frictional engagement with the heddle bar 4 and one end of the section 2 being secured by spring clamp 5 to the loom support 6, said section 2, further, being formed with an elongated slot 7 enlarged slightly at one end to receive the connecting bolt 8 carried by the section 1 and provided with the wing nut 9 whereby said adjustable plate sections are secured together. Guide clamps 10 also connect said plate sections to retain them in operative position.

Mounted to the curved end of the plate section 1 and to the upper end of the clamp 5 are the upright warp guides 11, the upper ends thereof being curved to provide a tread surface for the warp and secured to said warp guides are the resilient reed combs 12 between the several reeds of which the warp passes, the warp being manually introduced between the reeds when the channelled lock bar 13, hinged at one end to the comb frame, is raised to open or unlocked position, shown in dotted lines in Fig. 4. When the lock bar 13 is in closed or full line position the upper ends of the reeds project into the channelled portion thereof and the warp is locked or secured against removal from between the reeds.

A slack eliminator is mounted to the plate section 2 and comprises the substantially U-shaped inverted frame 14 to which the lock plate 15 is adjustably secured by the screw bolts 16, provided with wing nuts 17, said frame 14 and lock plate 15 being provided with the felt or composition pads 18 through which said screw bolts pass, said pads having their meeting faces recessed to receive the warp 19. When one screw bolt is removed the lock plate 15 with its pad 18 may be swung laterally upon the remaining screw bolt as a pivot to permit access to the warp, to remove or replace the same. In normal operative position the frame and plate together with the screw bolts and wing nuts provide a tension adjustment means for the warp passing therethrough to the drum.

The warp leaving the spools 20 of the spool rack 21 passes through the reeds of the reed comb and over the warp guides 11, through the slack eliminator and through the second

reed comb and over the second warp guide to the drum 22 where it is secured to and wound upon the several drum sections, each section comprising a plurality of pairs of drum guides 23, the upper ends of said guides being provided with angular nippers 24 that incline from their outer ends inwardly or toward each other so that should the warp tend to pass beyond the ends of the drum guides it will be returned therebetween by the nippers.

The sectional guide and tension plate is movable longitudinally along the heddle bar and loom support manually so that when one drum section is filled said plate may be shifted in a position to direct the warp to the next drum section. When one drum section is filled the pick-up comb 25 is applied to the warp at a point between the loom support and warp drum. This is a resilient reed comb provided with a hinged channel bar and the warp is manually placed between the reeds. The pick-up comb is now in substantially the position shown in Fig. 7. The comb is now manually moved to the dotted line position, Fig. 7, to permit the warp to be cut and thereafter secured to the next drum section to be supplied. The desired tension is given the warp by means of the wing nuts 17. The resiliency of the reeds of the reed combs permits knots or kinks in the warp to pass therethrough without hindrance.

What is claimed is:

1. In warp guiding and tension mechanism for warpers, sectional adjustable plates adjustably carried by the warper, warp guides carried by said plates, resilient reed combs secured to said warp guides, and slack elimination means mounted to one of said adjustable plates. 70

2. In warp guiding and tension mechanism for warpers, sectional adjustable plates adjustably carried by the warper, warp guides carried by said plates at the relatively remote ends thereof, resilient reed combs secured to said warp guides, and slack elimination means carried by one of said adjustable plates. 75

3. In warp guiding and tension mechanism for warpers, cooperating plates adjustably carried by the warper, warp guides carried by said plates, resilient reed combs secured to said warp guides, lock bars for said reed combs, and slack elimination means carried by said plates. 85

4. In warp guiding and tension mechanism for warpers, cooperating plates adjustably carried by the warper, warp guides secured to said plates, reed combs secured to said warp guides, and nippers carried by the warper drum guides. 90
